CLOTHESLINE HANGER

Eli L. Fink, Youngstown, Ohio

Application January 17, 1946, Serial No. 641,765

1 Claim. (Cl. 248—214)

1

This invention relates to a device to be employed in hanging a clothesline, particularly indoors.

The principal object of the invention is the provision of a clothesline hanger, several of which may be applied to suitable supporting structures in a dwelling house for example, so that a clothesline may be stretched therebetween.

A further object of the invention is the provision of a clothesline hanger providing means for satisfactorily spacing sections of clothesline hung thereon.

A still further object of the invention is the provision of a clothesline hanger, several of which may be positioned at spaced intervals along the lower side of a joist or a similar structural member in a dwelling house, and several more of which may be placed along the lower portion of a similar joist or other supporting member at some distance from the first mentioned hangers and in conjunction with one another will serve as means for hanging a clothesline therebetween and at the same time suitably space the clothesline so that clothes subsequently hung thereon will have sufficient air space therebetween for proper drying.

The clothesline hanger shown and described herein has been devised to form a simple and inexpensive device which can be easily installed in a dwelling in the basement thereof by attaching a plurality of the hangers to spaced joists.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a front elevation of a clothesline hanger formed in accordance with the invention and shows the same attached to a section of a joist.

Figure 2 is a side elevation of the clothesline hanger shown in Figure 1.

Figure 3 is a front elevation of a modified form of clothesline hanger attached to the supporting member.

Figure 4 is a cross sectional elevation taken on line 4—4 of Figure 3 of the clothesline hanger.

Figure 5 is a diagrammatic illustration repre-

senting a plurality of supporting members such as joists and showing a series of clothesline hangers affixed to the joists and a clothesline stretched therebetween.

5 By referring to Figures 1 and 2 of the drawings, it will be seen that the invention in its simplest form comprises a body member 10 of suitable material such as plywood, the uppermost end of which is provided with a pair of spaced openings 11 and 12 through which screws 13 and 14 may be positioned as in affixing the body member 10 of the clothesline hanger to a supporting member such as a joist 15. A rib 16 is transversely positioned on the body member 10 10 of the clothesline hanger downwardly from the uppermost end thereof and normally closely underlies the bottom of the supporting joist 15. Near the bottom of the body member 10 there are a pair of oppositely disposed, V-shaped 15 notches 17 and 18 which form means for directly engaging a clothesline to be hung on the clothesline hanger.

By referring to Figure 2 of the drawings, it will be seen that the horizontally positioned rib 25 16, which is affixed to the body member 10 by a plurality of screws 19, closely underlies the bottom of the supporting member or joist 15, and in connection with the screws 13 and 14 assists in holding the clothesline hanger in position on the supporting joist 15 at such time as a clothesline is positioned on a hanger and pulled in the direction of the arrow in Figure 2. Such action tends to move the horizontal rib 16 upwardly against the body of the joist and thereby cause 30 the body member 10 of the clothesline hanger to pivot thereon and tends to move the screws 13 and 14 outwardly of their position in the supporting member or joist 15.

It will be obvious to those skilled in the art that 40 other forms of the invention may be practiced and by referring to Figures 3 and 4 one such form may be seen.

In Figure 3 of the drawings, a clothesline hanger comprising a body member 20 may be 45 seen attached to a supporting member such as a joist 21. A pair of spaced openings 22 and 23 provide means for the attachment of the body member 20 to the joist 21 as by means of screws 24 and 25. A pair of tongues 26 are punched 50 from the material of the body member 20, which is preferably metal, and are inturned in approximately right angles to the vertical plane of the body member 20 to form means for registering with the bottom of the supporting member 55 21, as will be seen by referring to the cross sec-

tional elevation of Figure 4 of the drawings. The edges of the body member 20 are turned outwardly as at 27 on the sides, and on the bottom at 28 to form channels to increase the rigidity of the body member 20. It will be obvious to those skilled in the art that additional vertically extending channels or ribs may be formed in the body member 20, as desired.

A secondary body member 29 is affixed to the bottom surface of the body member 20 on the outturned flange 28 thereof to form a pair of oppositely disposed V-shaped slots 30 and 31. The body member 29 may be attached to the member 20 as by means of spot welding or may be bolted or otherwise affixed thereto. In any event, its corner sections adjacent the corners of the body member 29 are cut away to form the V-shaped slots 30 and 31 which may then be used for positioning a clothesline thereover.

By referring now to Figure 5 of the drawings, a schematic illustration may be seen wherein a plurality of joists 15 are represented in top plan view and it will be observed that a plurality of clothesline hangers 10 are positioned in rows on the outermost sides of two of the joists 15. A clothesline 32 is positioned over the plurality of clothesline hangers 10, first passing over one of the hangers 10 and then being stretched across this intervening space between the several joists 15 and then stretched across another of the clothesline hangers 10. This action is repeated until the full length of the clothesline has been hung or stretched between the plurality of clothesline hangers 10. In each instance the clothesline registers with the oppositely disposed, V-shaped notches formed in the sides of the clothesline hanger 10 and the width of the clothesline hanger 10 between the innermost portions of the V-shaped notches 17 and 18 forms the spacing indicated by the letter S in Figure 5 between the alternate lengths of clothesline 32. The spacings between the clothesline hanger 10 themselves forms the space indicated by the letter H in Figure 5 of the drawings. It will be observed that when the clothesline hangers 10 are properly spaced along the lengths of the joists 15 so that space between the hangers 10 is equal to the distance between the V-shaped notches 17 and 18 of the clothesline hanger 10, a uniformly spaced clothesline may be readily obtained by hanging the same on the various hangers, as shown.

It will be observed that the V-shaped notches 17 and 18 in the clothesline hanger 10 form simple means for affixing the endmost section of the clothesline, as a knot or two therein enables the end of the line to be held in the notch without the necessity of tying it to the hanger. It may be obviously wrapped around the hanger

once. In so affixing the end, the V-shaped notches by their formation will, in effect, clamp upon the clothesline as it wedges into the notches 17 and 18.

It will thus be seen that a simple, efficient and inexpensive clothesline hanger has been disclosed which may be easily installed in a dwelling house and which will securely position and support a clothesline hung thereon. It will be observed that the vertical height of the clothesline hanger positions the clothesline hung thereon at a satisfactory distance below the bottom of the joists thereby placing the clothesline at a height convenient for use in hanging clothes to be dried thereon.

Having thus described my invention, what I claim is:

A clothesline hanger comprising a section of thin material approximately twice as long as its width and having a pair of openings near one end thereof for the reception of screws used in attaching the hanger in a vertical position to a supporting member such as a floor joist, a transversely positioned rib located inwardly of the said openings and adapted to underlie the said supporting member, a secondary section of material attached to the bottom of the said section of material, the end portions of the said secondary section of material being tapered outwardly and downwardly so as to form in conjunction with the bottom of the said section of material V-shaped notches in the lower sides of the hanger for the purpose of receiving a clothesline and holding the same, the width of the hanger between the said notches spacing the clothesline hung on said hanger and the length of the said hanger spacing the clothesline from the said supporting member.
